A. J. FARNSWORTH ET AL

BAG

Filed March 15, 1920

Inventors;

Arthur J. Farnsworth
Eskelbert M. G. Glare

UNITED STATES PATENT OFFICE.

ARTHUR J. FARNSWORTH AND ETHELBERT M. ST. CLAIRE, OF SAN FRANCISCO,
CALIFORNIA, ASSIGNORS TO W. S. BEACH, OF SAN FRANCISCO, CALIFORNIA.

BAG.

Application filed March 15, 1920. Serial No. 366,047.

To all whom it may concern:

Be it known that we, ARTHUR J. FARNSWORTH and ETHELBERT M. ST. CLAIRE, citizens of the United States, residing at San Francisco, in the county of San Francisco and State of California, have invented a new and useful Bag, of which the following is a specification.

Our invention relates to improvements in bags that are intended for suspension from supporting devices, and particularly to such bags when made of paper or other relatively weak or easily torn material; and our purpose is to provide a simple and inexpensive bag that can be suspended in such a manner that the weight of its contents will be sustained by a relatively large portion of its periphery.

The accompanying drawing is a perspective view of a preferred form of our invention and illustrates the manner in which it is used in connection with a suitable supporting device.

The sides of the bag 1 have, at their upper edges, backwardly turned flaps 2 adapted for hanging upon the bag holding arms 3 of a supporting device, and for being retained in that position by means of suitable clamping devices or pressure bars such as shown at 4. In this manner the weight of the bag and its contents is distributed throughout the whole extent of its sides, and a greater loading is permissible than if the active supporting material were of less extent.

The upper corners of the bag, where the sides adjoin the ends, are slit downwardly for a distance as shown at 5. This is done to enable the bag holding arms 3 to rotate slightly when the mouth of the bag is being opened or closed while in position on the supporting device. Otherwise the material of the bag would be distorted and might be ruptured by the rotation of the arms. Re-inforcing patches 6 may be added to prevent the possible unintentional extension of slits 5.

A supporting device of the character herein indicated is fully described in U. S. Patent No. 1,307,439, issued to us June 24, 1919. The present invention was illustrated and described in said patent, but was not claimed therein.

We claim:

A relatively tall paper bag formed to leave an oblong opening in the top thereof, the material on two opposite sides of the bag terminating in ends extending beyond the ends of the other two sides to leave relatively long attaching flaps to be received by a bracket for suspending the bag with the opening therein held wide open, the corners of the bag adjacent said flaps being slit a short length of the corner folds, and patches attached to the bag sides around the corner folds to reinforce the folds at the termination of the slits.

ARTHUR J. FARNSWORTH.
ETHELBERT M. ST. CLAIRE.
